UNITED STATES PATENT OFFICE.

JOSEPH H. HUNTER, OF DETROIT, MICHIGAN.

METHOD AND MEANS FOR PREVENTING ACCIDENTS WITH ROLLING MILLS.

Application filed March 5, 1923. Serial No. 623,064.

To all whom it may concern:

Be it known that I, JOSEPH H. HUNTER, a citizen of the United States of America, residing at Detroit, in the county of Wayne 5 and State of Michigan, have invented certain new and useful Improvements in Methods and Means for Preventing Accidents with Rolling Mills, of which the following is a specification, reference being had 10 therein to the accompanying drawings.

The invention relates to safety devices for use in connection with rolling mills, and has for its primary objects the securing of instantaneous release in case a workman is 15 caught in the mill. In the present state of the art various safety appliances have been used in connection with such machinery, in practically all of which there is provided some means for throwing off the power or 20 stopping the machine in case of an accident. Inasmuch, however, as these machines are large in mass, there is a very considerable inertia factor, so that even where the power is instantaneously cut off, there will be considerable movement due to inertia. Thus, 25 in case a workman should catch his hand in the rolls before rotation can be stopped, he will be badly injured.

My improvement is based on the principle 30 that the drawing of anything between the rolls of the mill is due to friction. Therefore, if some means is instantaneously provided for eliminating friction, injury will be avoided. For example, with a rubber 35 mill the material introduced is of an adhesive nature and if the workman is once caught, it is almost impossible for him to overcome this adhesion. However, if he were to first coat his hand with some good 40 lubricant, there would be little danger of being caught and drawn between rolls. Therefore, broadly considered, my invention 45 consists in the application of a lubricant so as to instantaneously release a member, which might otherwise be drawn into the rolls. The invention further consists in a means for storing lubricant in proximity to the rolls and in the mechanism for instantaneously applying such lubricant in 50 case of necessity.

My invention is applicable to various constructions of rolling mills and other machines in which material is drawn in by friction, but I shall illustrate only diagrammatically one form, such as a rubber rolling 55 mill.

In the drawings:

Figure 1 is a diagrammatic end elevation of such a machine with my safety device applied thereto;

Figure 2 is a side elevation of a portion of Figure 1;

Figure 3 is a section through a modified construction.

A and A' represent two rolls mounted on 65 a suitable frame B and which revolve in opposite directions so as to draw the material into the throat C between said rolls. Suitably located above the rolls is a receptacle D for holding a large quantity of some 70 lubricating material. This may be either solid, liquid, or any form of substance, which when applied to a surface will break adhesion between the same and the material which is fed to the rolls. For instance, a 75 heavy oil would be suitable for such purpose, and, if desired, there may be combined with this material some antiseptic or medicinal material which will protect a wound from infection.

As specifically shown, the receptacle D is pivotally mounted at E upon a frame F rising from the frame B and is further supported by one or more catches G so that by 80 releasing such catches the contents of the receptacle will be instantaneously dumped. A hinged cover H may be arranged to protect the contents from dust and dirt without in any way preventing the discharge. For 85 releasing the catches I have shown a frame including bars I extending longitudinally on 90 each side of the machine and connected to pivoted levers or rockers J. Chains K are attached to these rockers and extend between the guide shives L to an actuating 95 arm M for releasing the catches. The arrangement is such that by pressing upon either of the bars I and at any point in the length of the machine, the catches G will be released and the contents of the receptacle D emptied. Also, the location of this 100 receptacle is such that in dumping the contents anything therebeneath will be completely covered with the lubricant.

While I have described this one specific 105 construction, it is evident that it is only one of many ways in which the lubricant might be instantaneously applied, and it is also evident that without any apparatus injury 110 might be prevented by first applying a lubricating coating to the hands of the workman. Still another modification of my invention

is in the form of a glove or mitten, such as O (Fig. 3) which is either made two ply with lubricating material between plies, or is lined with the material of a lubricating 5 nature which will prevent adhesion to the hand.

With all the various modifications the same basic principle is involved, viz, the breaking of adhesion so as to permit the operator to disengage himself from the rolls 10 or the material being fed thereto.

What I claim as my invention is:

1. The method of guarding against accidents with rolling mills or like class of machines, which consists in the application of 15 a lubricant to the surface of the member which is guarded.

2. The method of guarding against accidents with rolling mills and like machines, 20 which consists in quickly applying lubricant to the surface of a member caught by the machine.

3. A safety device for rolling mills or the like, comprising means for storing a lubricant in proximity to the machine, and means 25 under the control of the operator for instantaneously discharging said lubricant to coat the surface of a member caught in the machine.

4. A safety device for rolling mills or the like, comprising a receptacle for lubricant arranged in proximity to the machine, and means for instantaneously dumping said receptacle to coat with said lubricant the surface 30 of a member caught in the machine.

5. A safety device for rolling mills and the like, comprising means for storing lubricant in proximity to the machine, and means for discharging said lubricant to coat the 35 surface of a member to be guarded from 40 said machine.

In testimony whereof I affix my signature.

JOSEPH H. HUNTER.
